UNITED STATES PATENT OFFICE

2,427,230

PORTABLE COOLER

Harry Clemens Salzmann, Chicago, Ill.

Application October 28, 1946, Serial No. 706,260

4 Claims. (Cl. 62—31)

1

This invention relates to a new article of manufacture having the characteristics of a footrest, ottoman, hassock, or the like, and a refrigerator unit or cooler all contained in a unitary structure.

The main objects of this invention are to provide a device of this character having the characteristics of a footrest, hassock or ottoman, or the like, and a refrigerator unit or cooler, all arranged in a simple, compact unitary structure; to provide a device of this character wherein the temperature within the interior thereof is controlled and held uniform; to provide a structure of this character which is readily portable; to provide a structure of this character wherein Dry Ice or ice cubes may be utilized and disposed within housings placed about the interior of the unit; to provide a device of this character which will be attractive in appearance and economical to use; and to provide a device of this character which is simple in construction and inexpensive to manufacture.

An illustrative embodiment of this invention is shown in the accompanying drawings in which:

Figure 1 is a perspective view of my device.

Figs. 2 and 3 are cross sectional views taken on the lines 2—2 and 3—3 of Figs. 1 and 2, respectively.

Fig. 4 is a perspective view of the door of my invention, with parts shown broken away and in cross section.

The outer structure of my device is an upholstered ottoman, footrest, hassock or like device commonly used in most homes. The device disclosed in the drawings for illustrative purposes is an upholstered hassock having a top 1, vertical side walls 2, all suitably upholstered and finished to present a pleasing appearance to the eye. It will be appreciated that a suitable cushion may be placed on top 1 if desired. The side walls 2 are all secured in the usual manner to suitable skeletal framework 5 consisting of uprights and cross bars.

An inner liner preferably constructed of sheet steel, or the like, is secured to and within the interior area of the framework 5 as clearly shown in Figs. 2 and 3, and comprises a top 6, side walls 7, a back wall 8, all generally conforming to the shape of the side walls 2 of the exterior of the device, and a bottom wall 9, all integrally secured together at their marginal edges to form a chamber to receive articles to be stored therein.

The ice receptacle comprises a pair of elongated vertically disposed tubes 10 and 11, substantially square in cross section (see Fig. 3),

2

preferably constructed of sheet metal rigidly mounted on the rear wall 8 of the inner liner and spaced apart as shown in Fig. 3. The upper ends of the tubes 10 and 11 extend through the top wall 6 of the inner liner and into the area constituting an upper chamber defined by the top wall 6 of the inner liner and the top 1 of the device. Each tube is provided with a hinged cover plate 12 and access thereto is had by removing the top 1 or if the top 1 is hingedly secured, as shown in Fig. 2 by the hinge 13, then by raising the top 1 by lifting the same upwardly at its front edge as indicated by the dotted lines in Fig. 2 the same result is obtained.

In order to insure that the chamber formed by the inner liner retains its low temperatures after it has been cooled by the ice 14, in the form of cubes, crushed ice or Dry Ice, I pack insulation material 15 in the spaces defined by the framework 5, side walls 2 and the liner walls 7 and 9, as shown in Figs. 2 and 3. I provide a door 16 in the front of the device which is hingedly secured as at 17 to one of the side walls 2, whereby to provide access to the chamber formed by the inner liner. A pair of ice containers, in the form of elongated tubes 18—19 similar in substantially all details to the tubes 10—11, are rigidly secured to the inside face of the door 16, one adjacent each side edge thereof and each is provided with a cover plate 20 whereby access to the interior of the tubes is had.

The ice tubes 10—11 are provided with a connecting tube 21 positioned at the lower ends of the tubes 10—11 whereby any water or moisture accumulating in the tubes may be concentrated and drawn off through the pet cock or valve 22. A similar tube 23 and valve 24 is provided for the ice tubes 18—19 to perform the same function.

The device of my invention may also contain a utility drawer 25 positioned, as shown in Figs. 1 and 2, and disposed between the top 1 and top wall 6 of the inner liner.

It will now be apparent that this device may be used anywhere in the home and is particularly useful in parts of the home remote from the usual icebox, and will keep cool or chill bottled beverages, for instance, when the tubes 10—11 and 18—19 are filled with ice cubes or Dry Ice, and thereby provide a convenient small portable cooler.

Since there is always a possibility that condensation is likely to form on the inner side walls of the inner liner, I find it advisable to place a drip pan 26 on the lower wall 9 of the inner liner

to catch such condensation and prevent it from flowing outside of the cabinet.

Although one specific embodiment of this invention has been illustrated and described, it will be understood that numerous details may be altered or omitted without departing from the spirit of this invention as defined by the following claims.

I claim:

1. In a device of the class described; a framework having fully upholstered side walls and top, a door hingedly secured to said framework, an inner liner positioned within the interior area of said framework, a plurality of elongated ice tubes vertically disposed within the inner area of and mounted on said inner liner and on said door, and insulating means disposed in the spaces defined by said framework, the side and back walls of said inner liner, and said side walls.

2. In a device of the class described a framework having fully upholstered side walls and top, a door hingedly secured to said framework, an inner liner positioned within the interior area of said framework, a plurality of elongated ice tubes vertically disposed within the inner area of and mounted on said inner liner and on said door, means placing the tubes secured to said inner liner in communication with one another, means placing the tubes secured to said door in communication with one another, and insulating means disposed in the spaces defined by said framework the side and back walls of said inner liner, and said side walls.

3. In a device of the class described a framework having fully upholstered side walls and top, a door hingedly secured to said framework, an inner liner positioned within the interior area of said framework, a plurality of elongated ice tubes vertically disposed within the inner area

of and mounted on said inner liner and on said door, means placing the tubes secured to said inner liner in communication with one another, means placing the tubes secured to said door in communication with one another, an outlet port in one of said tubes secured to said inner liner, a second outlet port in one of said tubes on said door, and insulating means disposed in the spaces defined by said framework the side and back walls of said inner liner, and said side walls.

4. In a device of the class described a framework having fully upholstered side walls and top, a door hingedly secured to said framework, an inner liner positioned within the interior area of said framework, a plurality of elongated tubes disposed vertically within the inner area of and mounted on said inner liner and a plurality of vertically disposed elongated ice tubes positioned on the interior face of said door, means placing the tubes secured to said inner liner in communication with one another, means placing the tubes secured to said door in communication with one another; an outlet port in one of said tubes secured to said inner liner, a second outlet port in one of said tubes on said door, a drip pan positioned in the lower portion of said inner liner, and insulating means disposed in the spaces defined by said framework the side and back walls of said inner liner, and said side walls.

HARRY CLEMENS SALZMANN.
